**SECUREMENT FOR A ROUND-SIDE LOAD IN
A TRANSPORT VEHICLE**

Orville O. Clark, Joliet, and John F. Phelps, Downers Grove Township, Du Page County, Ill., assignors to United States Steel Corporation, a corporation of New Jersey

Filed Mar. 10, 1961, Ser. No. 94,805
2 Claims. (Cl. 105—369)

The present invention relates generally to the lading of transport vehicles and more particularly to an improved securement for a round-side load in a transport vehicle.

Although not restricted thereto the securement of our invention finds practical application in the lading of coils of wire or rod in railway box cars, and in that application we shall, in an exemplary way, describe it.

Prior to our invention the usual practice followed in loading coils of wire or rod in a railroad box car consisted of loading the coils in one half of the box car at a time and arranging the coils in parallel rows extending longitudinally of the car from one end thereof to a point adjacent the center door opening of the car. The coils in each row being disposed with the eyes thereof in horizontal alignment. Such a load unit was formed on each side of the center door of the car. One end of the rows of coils in each load unit abutted and was supported by the end wall of the car. The opposite end of each of the rows of coils was blocked by means of wooden 2 x 4's nailed to the floor and the sides of the car in abutting relation with the end coil in each row. This prior practice did not prove satisfactory in that the coils of wire or rod tended to shift and bounce in transit and usually arrived at their destination in poor condition.

Efforts were also made to block the load units by applying strapping across the free end of each of the load units and anchoring the ends of the strapping to the side walls of the car. However, this type of blocking also proved unsatisfactory due to the fact that the rounded side contour of the coils caused the strapping to slip and be displaced from engagement with the load when the coils shifted in transit.

It is, accordingly, the primary object of our invention to provide a securement for a round-side load in a transport vehicle which consists of applying an arrangement of metal banding straps and an open mesh metal fabric screen to the load in a unique manner so as to positively hold the load in place.

It is another object of our invention to provide a securement as described in the preceding object wherein the banding straps and metal open mesh fabric screen coact to prevent the securement from being displaced along the round sides of the load.

It is a further object of our invention to provide a securement for a round side load which is inexpensive to assemble and which can be applied to a load unit easily and quickly.

These and other objects will become more apparent after referring to the following specification and attached drawing in which:

The single FIGURE of the drawing is an isometric view partially diagrammatic showing a load of wire coils secured in a railroad box car by means of the securement of the invention.

Referring more particularly to the drawing reference character A designates the load-bearing floor surface of a conventional railroad box car having side walls B and an end wall C. A load unit L, consisting of three rows of wire coils W in upright position, is shown disposed on the floor A of the car between the side walls B with its sides extending substantially parallel with the side walls B and one end of the load unit abutting the end

wall C. The wire coils W are shown somewhat diagrammatically for purposes of clarity.

Such an arrangement of a load unit of wire coils in a box car is conventional and is not claimed as part of our invention the details of which will now be described.

5 The securement of our invention, designated generally by reference numeral 2, includes an open mesh wire fabric screen 4 disposed across the end of the load unit L remote from the end wall C of the car. A pair of vertically spaced banding straps 6 and 8, each interwoven through the mesh of the screen 4, extend from one side wall B of the box car to the other.

10 Each of the banding straps 6 and 8 is made up of a pair of lengths of strapping 6', 6'' and 8', 8'', respectively, each of which is anchored by one end to a side wall of the car intermediate the end wall C and the center door opening E of the car. The free ends of each pair of lengths of strapping 6', 6'' and 8', 8'' are overlapped and have been tensioned and then sealed by means of conventional band seals D.

15 The lowermost banding strap 6 extends in a horizontal plane below the central horizontal plane through the load while the upper banding strap 8 is above the central horizontal plane through the load. The lowermost banding strap 6 serves to prevent the wire fabric screen 4 from moving upwardly along the end of the load unit and the screen 4 prevents the uppermost strap 8 from being displaced upwardly. The banding straps 6 and 8 together with the mesh screen 4 function to positively secure the load L in position.

20 In operation, before the load unit L of wire coils is placed in the car the vertically spaced pairs of lengths of banding strapping 6', 6'' and 8', 8'' are each anchored by one end to the side walls B of the box car by any suitable means, such as anchor plates F, at points intermediate the center door opening and the end wall of the car. After the strapping lengths have been thus anchored to the side walls of the car, they are laid on the floor of the car adjacent the side walls. The wire coils W are then moved into the car and arranged into the load unit L. After the load unit L has been thus arranged in the one end of the car the open mesh wire fabric screen 4 is placed in upright position across the ends of the load unit L as shown. The strapping lengths are then interwoven through the mesh of the screen, overlapped, tensioned, and then interlocked with banding seals D in the conventional manner to form the lower and the upper banding straps 6 and 8. The interweaving of the straps through the mesh of the screen prevents the straps from shifting and results in the coils of wire being positively held in position during shipment. It will be noted that the lower strap 6 applies a downward force to the mesh screen and prevents it from moving upwardly while the screen applies a downward force to the upper banding strap 8 and prevents it from moving upwardly. Coaction between the banding straps and the wire fabric screen anchors the securement in place and prevents it from being displaced upwardly along the round side of the load unit.

25 40 45 50 55 60 While one embodiment of our invention has been shown and described, it will be apparent that other adaptations and modifications may be made without departing from the scope of the following claims.

We claim:

65 1. Securement for a round-side load in a transport vehicle having a load-bearing floor surface, spaced side walls and an end wall, said load being disposed on said floor surface between said side walls with one end thereof abutting said end wall and its other end disposed remote from said end wall, said remote end of said load being substantially flat, the axis of said load being generally horizontal and extending generally parallel with said

side walls, said securement comprising a metal mesh screen disposed transversely across said remote end of said load, and a pair of vertically spaced banding straps each interwoven through the mesh of said screen along substantially the entire horizontal length of the screen and extending from one side wall to the other, each of said straps being secured at its ends to said side walls intermediate the ends of the load, the interwoven portion of the lowermost one of said banding straps being in a horizontal plane above the secured end portions thereof whereby said lowermost strap exerts a downward force on said screen to maintain the latter in position across said remote end of said load, said screen being effective to maintain the uppermost one of said straps in position across said remote end of said load when said screen is held down by said lowermost strap.

2. Securement for a round-side load in a transport vehicle having a load-bearing surface, spaced side walls and an end wall, said load being disposed on said floor surface between said side walls with one end thereof abutting said end wall and its other end disposed remote from said end wall, said remote end of said load being substantially flat, the axis of said load being generally horizontal and extending generally parallel with said side walls, said securement comprising a metal mesh screen disposed transversely across said remote end of said load,

5
10

and a pair of vertically spaced banding straps each interwoven through the mesh of said screen along substantially the entire horizontal length of the screen and extending from one side wall to the other, each of said straps being secured at its ends to said side walls intermediate the ends of the load, the lowermost one of said straps being in a horizontal plane below the central horizontal plane through said load and the uppermost one of said straps being in a horizontal plane above the central horizontal plane through said load, the interwoven portion of said lowermost one of said straps being in a horizontal plane above the secured ends thereof whereby said lowermost strap exerts a downward force on said screen, said lowermost one of said straps being effective to maintain said screen in position across said remote end of said load, and said screen being effective to maintain said uppermost one of said straps in position across said remote end of said load.
